(57) **CLAIM**

The ornamental design for a linear actuator and control box combination, as shown and described.

DESCRIPTION

FIG. 1 is a perspective top view of a linear actuator and control box combination showing my design.

FIG. 2 is a perspective bottom view thereof;

FIG. 3 is an elevational right side view thereof;

FIG. 4 is an elevational left side view thereof;

FIG. 5 is a top plan view thereof;

FIG. 6 is a bottom plan view thereof;

FIG. 7 an elevational front view thereof; and,

FIG. 8 an elevational rear view thereof.

The linear actuator is shown with a symbolic break in its length. The appearance of any portion of the linear actuator between the break lines forms no part of the claimed design. Any portion of the article depicted in broken lines forms no part of the claimed design.
